ATTENTION ATTRACTING DEVICE

Homer J. Hetrick, Akron, Ohio

Application October 31, 1933, Serial No. 696,016

16 Claims. (Cl. 40—28)

This invention relates to advertising display or attention attracting devices for washing or like machines.

The general purpose of the invention is to provide an attachment for washing or like machines including means adapted to be secured to the agitator of said machines and extending upwardly therefrom so as to be visible at distances from the machine and adapted to be reciprocated or oscillated or otherwise moved by operation of the agitator in the machine to attract the attention of passers-by, as for example in a store, or on the pavements outside the window of a store, in which the washing machine with the improved attachment is on display.

A further purpose of the invention is to provide a display or attention attracting device of this sort including electrically operable means carried on said attachment, for example, an electric lamp, and means for supplying electricity to said electrically operable means while the same is being oscillated, reciprocated or otherwise being moved by the agitator of the washing or like machine.

The foregoing and other purposes of the invention are attained in the attachments illustrated in the accompanying drawings and described below. It is to be understood that the invention is not limited to the particular forms thereof shown and described.

Of the accompanying drawings,

Figure 1 is an elevation partly broken away of a washing machine of that type having a horizontally oscillating agitator showing display or attention attracting device embodying the invention attached thereto in operative position;

Figure 2 is an enlarged sectional part plan on line 2—2 of Figure 1;

Figure 3 is a section on line 3—3 of Figure 2;

Figure 4 is a part elevation partly broken away and partly in section of a washing machine of that type employing a vertically reciprocable agitator having a display or like device attached thereto in accordance with the invention;

Figure 5 is an enlarged sectional elevation on line 5—5 of Figure 4;

Figure 6 is an enlarged section on line 6—6 of Figure 5, and

Figure 7 is an enlarged section on line 7—7 of Figure 5.

Referring first to Figures 1 to 3 of the drawings, the numeral 10 designates the usual clothes receptacle or tub of a known type of washing machine in which is arranged a horizontally oscillatable agitator 11 operable in any suitable or

known manner as by means of an electric motor and a suitable transmission (not shown).

The improved attachment comprises a standard 12 formed with a collar 13 at its lower end adapted to fit over the top portion of agitator 11 and which may be secured thereto and centered thereon in any suitable way as by means of set screws 14, 14. The standard 12 may carry in a position above the top of the receptacle or tub 10, any desired form of advertising or attention attracting device which will be moved for the purpose stated by the operation of the agitator.

In accordance with the preferred adaptation of the invention, the standard 12 may carry at its top one or more electrically operable devices such as electric lamps 15, 15, which may be arranged in a translucent or other suitable shade 16 carrying suitable advertising display legends, symbols or devices for the stated purpose.

The standard 12 may be hollow as shown and leads 17, 17 (Figure 3) may be extended down from the electrically operated devices or lamps 15, 15, respectively, to contact rings 18, 18 mounted on blocks 19, 19 of suitable insulating material fitted in a circumferential groove 20 about the outer periphery of collar 13.

The contact rings 18 are preferably concealed by a collar 21 surrounding, but preferably not contacting with collar 13 and supported on a hollow arm 22 which may be mounted on the tank or receptacle 10 by means of a clamp 23 having spaced legs 23^a, 23^b for engaging over the upper edge and embracing the upper portion of the wall of tub 10. A set screw 25 having a rubber or other soft non-marring foot 25^a may be threaded through the outer leg 23^b into engagement with a peripheral groove 10^a adjacent the top of tub 10 and set screws 26 and 27 with similar non-marring feet may be threaded respectively through the lower portions of the inner and outer legs 23^a and 23^b into contact with the wall of tub 10 to secure arm 22 rigidly to the tub 10 with its collar 21 substantially concentrically arranged about collar 13.

Collar 21 has housed therein a block 28 of insulating material in which are mounted contact brushes yielding urged against rings 18 by springs 30, 30. Leads 31, 31 are connected to brushes 29 and extend outwardly through arm 22 to a suitable electrical switch plug 32 in which may be engaged a known type of Y-connecting electrical fitting 33 from which extends one connector or leads cord 34 for the motor (not shown) of the washer and another connector or leads cord 35 to a source of power.

With the arrangement shown it will be apparent that when electricity is switched on at 32, the lamps 15 will be lighted and the motor (not shown) of the washer will be driven. If now the 5 clutch (not shown) of the washer is engaged, the agitator 11 will be oscillated and with it the standard and illuminated display will oscillate serving to attract the attention of passers-by. Illumination of the display will be maintained 10 regardless of the range of the oscillations or regardless of the particular angles defining the range thereof depending upon the point of engagement of the clutch because of the contact of brushes 29 with rings 18.

15 In Figures 4 to 7 a washer is shown which comprises a tub or receptacle 49 in which are vertically reciprocable agitator cups 41, 41 secured on a vertically-reciprocated member 42 slidable in a hollow post 43 and operated by a suitable motor 20 and transmission (not shown) in a known manner.

A standard 44, similar to standard 12 of Figures 1 to 3, may be similarly secured to the reciprocable agitator 42 by a collar 44^a formed on the lower 25 end of the standard. A downward extension 45 from the standard 44 and which may be integral therewith, carries leads 46 from the lamps or other electrical devices which are connected with brushes 47, 47 (see Figures 4 and 7) mounted in 30 an insulating block 48 at the lower end of the extension, the brushes being yieldingly urged by springs 49, 49 into contact with conductor strips 50, 50. Conductor strips 50 extend vertically of a block 51 of insulating material, which block 35 is clamped onto post 43 by similar upper and lower clamps 52, 52. A lug 53 attached to the extension 45 engages in a vertical groove 54 in the block 51 (see Figures 4 and 6) whereby the agitator and the attached standard 44 are caused 40 to so reciprocate along a single vertical path as to maintain brushes 47 in contact with the conductor strips 50 at all times.

The conductor strips 50 have connected thereto leads in a conductor cord 55 which is extended 45 through a hollow arm structure 56 to an electrical switch plug 57 similar to switch plug 32 and connected in a similar way to a source of electrical power and to the motor (not shown) of the washer. The arm structure 56 extends across the 50 bottom of tub 40 and then vertically upwardly along a wall thereof to clear the agitators 41 and the arm structure may be clamped on the top edge of the washer by a suitable clamp 58.

In the form of the invention illustrated in Figure 4, the switch 57 may be operated to start the motor of the washer and to operate the lamps or other electrical devices on the standard 44. When the agitator 41 is vertically reciprocated (usually by engaging a clutch, not shown) the standard 60 44 reciprocates with it and the brushes 47 reciprocating on the conductor strips 50 maintain the supply of electricity to the standard 44 at all times.

It will be apparent from the foregoing that 65 simple effective display or attention attracting devices have been provided for washing or like machines by the invention. Obviously modifications of the invention other than those disclosed herein may be resorted to without departing from the spirit thereof or the scope of the appended 70 claims. It will be apparent that the device may be readily adapted as an illuminating attachment for use by the operation of a washing machine during the operation of washing clothes. The 75 parts may be suitably protected where it is re-

quired to prevent moisture from disturbing its normal operation.

What is claimed is:

1. An attachment for a washing machine including a tub and an agitator mounted to move in the tub, said attachment comprising a standard having means thereon for attaching it to said agitator, said standard extending above said tub and adapted to carry advertising display or attention attracting devices thereon above the top of the 10 tub, an illuminating device carried by the standard, and means for conducting electricity to said device during movement of the agitator.

2. An attachment for a washing machine including a tub and an agitator mounted to move 15 in the tub, said attachment comprising a standard having means thereon for attaching it to said agitator, said standard extending above said tub and adapted to carry advertising display or attention attracting devices thereon above the top 20 of the tub, an illuminating device carried by the standard, means for conducting electricity to said device during movement of the agitator, said means comprising a member having means associated therewith for securing said member in a 25 fixed position on the tub, said member carrying brushes to which electrical leads are connected, and conductor elements associated with and moving with the standard upon movement of the agitator, said conductor elements being so arranged on the standard as to maintain contact with said brushes at all times during movement 30 of the agitator.

3. An attachment for a washing machine including a tub and an agitator therein mounted 35 to move to and fro in the tub, said attachment comprising a standard having means associated therewith for securing the attachment to the agitator, said standard extending above said tub and adapted to carry advertising or attention 40 attracting devices thereon above the top of the tub, an illuminating device carried by the standard, and means for conducting electricity to said device during movement of the agitator.

4. An attachment for a washing machine including a tub and an agitator therein mounted to oscillate horizontally in the tub, said attachment comprising a standard having means associated therewith for securing the attachment to the agitator, said standard extending above said tub 50 and adapted to carry advertising or attention attracting devices thereon above the top of the tub, an illuminating device carried by the standard, and means for conducting electricity to said device during movement of the agitator.

5. An attachment for a washing machine including a tub and an agitator therein mounted to reciprocate vertically in the tub, said attachment comprising a standard having means associated therewith for securing the attachment to the agitator, said standard extending above said tub and adapted to carry advertising or attention 60 attracting devices thereon above the top of the tub, an electrically operable illuminating device carried by the standard, and means for conducting electricity to said device during movement of the agitator.

6. An attachment for a washing machine including a tub and an agitator therein mounted to move to and fro in the tub, said attachment 70 comprising a standard having means associated therewith for securing the attachment to the agitator, said standard extending above said tub and adapted to carry advertising or attention 75 attracting devices thereon above the top of the tub,

an electrically operable illuminating device carried by the standard, means for conducting electricity to said device during movement of the agitator, said means comprising a member having means associated therewith for securing said member in a fixed position on the tub, said member carrying brushes to which electrical leads are connected, and conductor elements associated with and moving with the standard upon movement of the agitator, said conductor elements being so arranged on the standard as to maintain contact with said brushes at all times during movement of the agitator.

7. An attachment for a washing machine including a tub and an agitator therein mounted to oscillate horizontally in the tub, said attachment comprising a standard having means associated therewith for securing the attachment to the agitator, said standard extending above said tub and adapted to carry advertising or attention attracting devices thereon above the top of the tub, an electrically operable illuminating device carried by the standard, means for conducting electricity to said device during movement of the agitator, said means comprising a member having means associated therewith for securing said member in a fixed position on the tub, said member carrying brushes to which electrical leads are connected, and conductor rings associated with and moving with the standard upon movement of the agitator, said conductor rings being so arranged on the standard as to maintain contact with said brushes at all times during movement of the agitator.

8. An attachment for a washing machine including a tub and an agitator therein mounted to reciprocate vertically in the tub, said attachment comprising a standard having means associated therewith for securing the attachment to the agitator, said standard extending above said tub and adapted to carry advertising or attention attracting devices thereon above the top of the tub, an electrically operable illuminating device carried by the standard, means for conducting electricity to said device during movement of the agitator, said means comprising a member having means associated therewith for securing said member in a fixed position on the tub, said member carrying conductor strips thereon, and brushes associated with and moving with the standard upon movement of the agitator, said conductor strips being so arranged on said secured members as to maintain contact with said brushes at all times during movement of the agitator.

9. An attachment for a washing machine including a tub and a movable agitator therein, said attachment comprising a standard having means associated therewith for securing said standard to said agitator so as to project above said tub and to be moved by the agitator, electrically illuminated means carried by the standard above the tub, and means for supplying electricity to said illuminating means during movement of the agitator.

10. An attachment for a washing machine including a tub and a movable agitator therein, said attachment comprising a standard having means associated therewith for securing said standard to said agitator so as to project above said tub and to be moved by the agitator, electrically illuminated means carried by the standard above the tub, means for supplying electricity to said illuminating means during movement of the agitator, said supplying means including means for supporting conducting brushes, and

means for supporting conductor elements on the relatively moving parts and so arranged as to contact at all times during movement of the standard.

11. An attachment for a washing including a tub and a movable agitator therein, said attachment comprising a standard having means associated therewith for securing said standard to said agitator so as to project above said tub and to be moved by the agitator, electrically illuminated means carried by the standard above the tub, means for supplying electricity to said illuminating means during movement of the agitator, said supplying means including means for supporting conducting brushes and means for supporting conductor elements on the relatively moving parts and so arranged as to contact at all times during movement of the standard, and means for concealing said conductor brushes and said conductor elements.

12. An attachment for washing machines including a tub open at its top and a movable agitator in the tub, said attachment comprising a supporting member having means associated therewith for attaching the member to said agitator, an electrically operable illuminating device carried by the supporting member above the top of the tub, means associated with the supporting member for conducting electricity to said device and including conductor elements movable with the standard, an arm having means associated therewith for securing the arm on a wall of the tub to extend into cooperative relation with said moving conductor elements, contact elements carried by said arm and cooperating with said conductor elements, and means for conducting electricity to said contact elements.

13. An attachment for washing machines including a tub open at its top and a horizontally oscillatable agitator in the tub, said attachment comprising a supporting member having means associated therewith for attaching the member to said agitator, an electrically operable illuminating device carried by the supporting member above the top of the tub, means associated with the supporting member for conducting electricity to said device and including conductor rings movable with the standard, an arm having means associated therewith for securing the arm on a wall of the tub to extend into cooperative relation with said moving conductor rings, contact brushes carried by said arm and cooperating with said rings, and means for conducting electricity to said contact brushes.

14. An attachment for washing machines including a tub open at its top and a vertically reciprocable agitator in the tub, said attachment comprising a supporting member having means associated therewith for attaching the member to said agitator, an electrically operable illuminating device carried by the supporting member above the top of the tub, means associated with the supporting member for conducting electricity to said device and including conductor strips vertically arranged in association with an arm, said arm having means associated therewith for securing the arm on a wall of the tub, contact brushes carried by said standard and cooperating with said strips, and means for conducting electricity to said strips.

15. An attachment for washing machines including a tub having an open top and an agitator movable therein, said attachment comprising a member having means associated therewith

for securing the same to the agitator, said member carrying an electrically operable illuminating device above the tub, and means for conducting electricity to said device including conductor elements associated with said member to move therewith upon movement of the agitator, other conductor elements for engaging said elements and maintaining contact therewith as said elements move, an arm for supporting the second-named conductor elements in cooperative relation to the first-named conductor elements, said arm carrying electrical leads to said

conductor elements, and means for securing said arm on the wall of said tub.

16. An attachment for a washing machine including a tub and an agitator mounted to move in the tub, said attachment comprising a standard having means thereon for attaching it to said agitator, said standard extending above said tub and adapted to carry advertising display or attention attracting devices thereon above the top of the tub, and an illuminating device carried by the standard. 10

HOMER J. HETRICK.
